UNITED STATES PATENT OFFICE.

R. H. LAMBORN, OF ALTOONA, PENNSYLVANIA.

IMPROVEMENT IN COAL-MINING APPARATUS.

Specification forming part of Letters Patent No. 42,669, dated May 10, 1864.

To all whom it may concern:

Be it known that I, R. H. LAMBORN, of Altoona, in the county of Blair and State of Pennsylvania, have invented a new and useful Coal-Mining Apparatus; and I do hereby declare the following to be a full and correct description of the same, reference being had to the accompanying drawings, in which—

Figure 1 is a top view of my improved machinery or apparatus, and Fig. 2 is a front elevation of the same.

The same part is indicated by the same letter of reference wherever it occurs.

The nature of this invention consists in the construction and arrangement of a new and useful apparatus for performing by machinery that part of the operation of mining coal which is called by miners "bearing in," and which is now performed by hand with a pick, the said apparatus consisting of a sectional track, a self-moving truck or car, supporting a steam or compressed-air engine, operating chisels or picks of any suitable kind. The coal to be mined usually lies upon a stratum of slate, which forms the "floor" of the mine, and is covered by a similar stratum, which forms the roof.

In order to obtain a space into which the coal can be forced by blasting, it is necessary to cut in the face of the coal, about midway of its height, a wedge-shaped horizontal channel, toward which the coal is to be driven by the blast, both from above and below. The operation of cutting this channel is called "bearing in," and to perform this operation by means of tools driven by power is the object of my invention.

To enable others to make use of my apparatus, I will now proceed to describe its construction and mode of operation, referring to the drawings, wherein is represented a steam or air engine placed upon a self-moving truck, and prepared for operating mining-tools or chisels of various kinds.

A marks one section of the track on which the truck moves. This track is made in sections, so that when the truck reaches the end of one section and passes on to a second one the first section can be taken up and laid in front of the second, and so a continuous track be provided for the advance of the apparatus as its work progresses. One side of this track is provided with a rack, H, which engages

with teeth attached to the inner side of one of the wheels, B', of the truck C. The other wheels, B, of the truck are similar to the ordinary railway-car wheels, and are controlled by brakes m, operated by the treadle l or in any other convenient manner. Upon these wheels is supported the body of the truck C, which carries the engine for operating the mining-tools. The engine is driven either by steam or by compressed air, and in either case the operating-fluid is conveyed to the engine through suitable tubing, the engine which supplies the steam or effects the compression of the air being located at the mouth of the mine.

The engine is similar in general construction to the common high-pressure engine. It has a cylinder, D, in which a piston is caused to reciprocate, in the usual manner, by means of steam or compressed air admitted into valve-chests F F, controlled by slide-valves of the ordinary construction.

E marks the piston-rod, to the forward end of which is to be attached the chisel G or other suitable tool, by which the work of channeling is to be done. The rear end of the piston-rod is attached to a cross-head, L, which works on guide-rods M and the valve-rod I. As the cross-head reciprocates it comes in contact with the stops e and f on the valve-rod i, and thus regulates the action of the valves, and consequently the stroke of the piston, and of the tool attached thereto. The stops e and f are fixed at any desired position on the rod I by means of set screws. The rod I operates the bell-crank lever K, the lower arm of which works the ratchet-wheel h, which is also engaged by spring dog d, attached to the frame of the truck. To the outer end of the shaft b of this wheel is attached the cogged pinion g, which gears into and drives the cog-wheel B', by the rotation of which the truck is advanced along the track. The position and movements of the valve-rod I can be controlled, when desired, by the forked hand-lever j, which receives and holds said rod, and is hinged at a to the frame of the truck. This lever is to be worked by hand whenever it is desirable to move the piston back when it shall have stopped in the midst of a stroke, or to place the piston in any desired position.

The piston, piston-rod, piston-head, and

cross-head together constitute the weight, which, being urged forward by the propelling-power, acquires momentum sufficient to cut into the coal. The force of this momentum is seconded by the direct action of the steam or compressed air, so that the action of the tool combines the percussive effect of a drill with the continuous operation of a mortising-chisel. The piston-rod is made to rotate, as far as may be desired, at every stroke by any of the usual devices employed for rotating rock-drills.

N marks the steam inlet-pipe, of which the branch O leads to the forward and P to the rear end of the cylinder. A cock, e, gives control over the supply of steam to the forward end of the cylinder, since it is not necessary to employ the full force of the air or steam to bring back the chisel, after it has struck its blow.

Q marks the exhaust, to which a flexible tube may be attached, in order that the exhaust air may be so directed as to blow out the chips, and thus clear away the channel behind the chisel, and also contribute to the ventilation of the mine.

It will be observed that the cylinder D is placed upon the truck at an angle, so that the chisel shall not strike a blow directly perpendicular to the face of the coal, but strike at an inclination of about ten degrees.

The operation of the apparatus is as follows: The sectional track is laid down upon the floor of the mine and firmly jacked from the roof against the floor. The truck C is placed upon the track, and the piston of the cylinder D set in motion by the admission of the compressed air or steam, conducted from the engine at the mouth of the mine. The chisel or other tool at the end of the piston-rod is driven against and into the face of the coal, and begins the cutting of the channel before alluded to. As the piston reciprocates it causes the lever K, whose fulcrum is at n, to vibrate, and drive the ratchet-wheel h, the dog d preventing the motion of the wheel h from being reversed. The wheel h, by means of pinion g, drives the cogged wheel B', which works into the rack H, and causes the truck to advance a short distance at every stroke of the piston. Thus the apparatus is moved forward automatically along the face of the coal, cutting as it goes.

It will be observed that the machine is moved forward only at the moment that the

chisel is drawn back out of the channel that it is cutting.

The direction in which the machine advances is indicated by the arrow in Fig. 1.

The chips made by the operation are blown from the channel by the exhaust, which is conveyed by a pipe and projected into the cut in the coal.

The operator who attends the machine stands on the truck, and regulates its operation, turning on air or steam when required to drive the chisel, and governing, by means of cock e, the amount that shall flow into the forward end of the cylinder. He is also enabled, by means of the lever j, connected with the valve-rods, to regulate the force of the blow and the length of stroke, and, by the wheel h, to control the advance of the truck. When the truck approaches the front end of the section of track on which it is moving, a second section is laid down in advance of it, and secured as before described, so that the progress of the machine shall be continuous.

Having thus fully described my invention, what I claim therein as new, and forming an improved apparatus for coal-mining, and desire to secure by Letters Patent, is—

1. The arrangement and combination of the cylinder D with the truck C in such a manner as to give the piston-rod E (to the end of which the chisel is attached) an angle with the face of the coal, the force of the blow given by said piston-rod being regulated by the connection of said rod with cross-head L, valve-rod I, and adjustable stops e f, as set forth.

2. In combination with the foregoing, the sectional tracks, constructed, secured, and employed as and for the purpose herein specified.

3. The combination of wheel h, pinion g, and cog-wheel B' with the sectional tracks constructed, as herein described, to give the necessary forward movement to the truck by their connection with valve-rod I and lever K.

4. The employment, in an apparatus such as described, of the exhaust air or steam to keep the channel clear of chips and dust in the manner described.

The above specification of my said invention signed and witnessed, at Altoona, this 8th day of December, A. D. 1863.

R. H. LAMBORN.
